(57) **CLAIM**

The ornamental design for a water container, as shown and described.

DESCRIPTION

FIG. 1 is a top, front perspective view of a water container, embodying my new design;

FIG. 2 is a front view of the container embodiment depicted in FIG. 1.

FIG. 3 is a back view.

FIG. 4 is a top view.

FIG. 5 is a bottom view.

FIG. 6 is a left side view; and,

FIG. 7 is a right side view.

The broken line showing of a hose and shower head in the FIG. 1 view is included for the purpose of illustrating environment of the water container and forms no part of the claimed design.
